UNITED STATES PATENT OFFICE.

JOHN NEUMANN, OF CHICAGO, ILLINOIS, ASSIGNOR OF ONE-HALF TO H. N. CLAUSSEN,
OF CHICAGO, ILLINOIS.

SEALING-DISK FOR BOTTLE-STOPPERS.

1,230,594.

Specification of Letters Patent. Patented June 19, 1917.

Application filed March 2, 1916. Serial No. 81,611.

To all whom it may concern:

Be it known that I, JOHN NEUMANN, a citizen of the United States, residing at 1412 Kesner Bldg., Chicago, in the county of Cook and State of Illinois, have invented 5 certain new and useful Improvements in Sealing-Disks for Bottle-Stoppers, of which the following is a specification.

My invention relates to improvements in sealing disks for bottle stoppers, the mode 10 of manufacture of said disks and the improvement in the art of sealing bottles by the aid of said disks.

In the specific embodiment of my improvement herein shown and described, the 15 interior of the flanged fastener cap instead of containing a thin disk of cork as usually employed is provided with a compressible disk of paper formed of two flat circular 20 side portions separated by an interposed central circular corrugated portion which is connected at the outer margins of its corrugations to the inner surfaces of the side portions, the whole being dipped and impregnated in melted and liquid wax and 25 then allowed to cool to form a waxy coating upon the outer surfaces and around the edges of the disk.

In manufacturing my improved sealing 30 disks, I prefer to cut the disks to the desired circular form in suitable dies, then dip them in melted wax and finally allow them to cool after which they are ready for use and are fitted in place in the flanged fastener 35 caps.

The cork filling employed in the ordinary stopper is relied upon to seal the mouth of the bottle when it is compressed upon the same, with my improved paper disk, 40 the same sealing effect is secured and at the same time a more perfect, efficient and complete sealing is obtained around the edges of the disk by the forcing out of the wax through the compression of the disk which 45 fills all the small interstices between the disk edges and the surface of the bottle neck.

The objects of my invention are to produce an exceedingly cheap, efficient and perfect sealing disk for flanged fastener caps 50 for bottles or the like, to so construct these disks that they are quickly and cheaply manufactured, and to so arrange the said disks in the fastener caps that a perfect sealing effect is produced when the caps are 55 forced into place on the mouths of bottles.

The above and other objects I accomplish as hereinafter set forth in the following description and as particularly pointed out in the appended claims reference being had to the accompanying drawings in which an embodiment of my invention is shown. 60

In the drawings:

Figure 1 represents a top plan view of my improved sealing disk.

Fig. 2, is a central section through the 65 disk on line 2—2 Fig. 1.

Fig. 3, is a fragmentary view of the neck of a bottle partially in section with a fastener cap and sealing disk in position thereon.

Fig. 4, is a fragmentary top plan of a 70 sheet of material from which the disks are cut.

Fig. 5, is an edge view of the sheet shown in Fig. 4.

In referring to the embodiment of my 75 invention shown in the accompanying drawings in detail, like numerals designate corresponding parts.

My improved sealing disk is formed from a fairly thick compressible composite sheet 80 of suitable material such sheet of suitable material such as corrugated paper impregnated in and coated with wax.

In the specific embodiment shown in the 85 accompanying drawings, the disk is composed of two companion side portions or sections, 1, which are flat and circular in form and are in parallel separated arrangement and an interposed corrugated portion 2, arranged between the side portions and 90 connected at its marginal bends to the inner surfaces of the side portions.

The disk is dipped in a melted and liquid wax such as heated bees wax after it is cut or the sheet of material may if in certain 95 circumstances be dipped before the disks are cut therefrom.

After coating the disks are allowed to cool, forming a thin coating 3 of wax on the extension side surfaces of the disk and also 100 at least partially providing a filling 4 of wax around the circular marginal edge thereof.

My improved disk is inserted in a flanged cap 5, fitting the same snugly as shown in 105 Fig. 3, and the cap is forced upon the top mouth of a bottle 6 with its depending flange 7 bent inwardly over and locked around the bead 8 of the bottle neck in the usual manner.

In securing the fastener cap upon the bottle, the disk is compressed between the top edge of the bottle mouth and the cap, forcing the wax out from between the side portions of the disk and filling all the minute interstices between the circular edge of the disk and the interior of the bottle neck thereby producing a perfect and complete seal which is both air and liquid tight.

10 My improvement is especially adapted for bottling beer and other liquids.

When employed in bottles that are heated for sterilization purposes, such as beer bottles, the wax in the disk is partially melted 15 by the heat and runs sufficiently to fill in and render the seal more perfect if that were possible.

While I have described and illustrated a preferred form of construction for carrying 20 my invention into effect, the same is capable of a wide range of variation, alteration, modification and change without departing from the spirit of my invention, I therefore do not wish to be limited to the above 25 construction but desire to avail myself of all such variations, alterations, modifications and changes as fairly fall within the scope of the appended claims, or may be construed to be

within the same by involving the doctrine of equivalents.

What I claim as my invention and desire to secure by Letters Patent is:—

1. A seal for bottle stoppers comprising a compressible disk having peripheral recesses, and a viscous sealing substance filling 35 said recesses.

2. A sealing disk for bottle stoppers comprising upper and lower cover members, a compressible corrugated element between said members forming peripheral recesses 40 in the disk, and a waxlike filling in said recesses.

3. A sealing disk for bottle stoppers comprising upper and lower cover members, a compressible mutilated element between 45 said members forming peripheral recesses in the disk, and a waxlike filling in said recesses.

4. A compressible sealing disk of a plurality of separated paper portions, a bent 50 paper portion connecting said separated portions, and a waxlike edge filling for said disk.

In testimony whereof I affix my signature.

JOHN NEUMANN.
